ANIMAL PULL TOY

William S. Loeb, Philadelphia, Pa., assignor to Wilkening Manufacturing Company, Philadelphia, Pa., a corporation of Delaware

Application April 29, 1957, Serial No. 45,931

Term of patent 7 years

(Cl. D34—15)

Fig. 1.

Fig. 2.

Fig. 3.

The opposite side, not shown, has substantially the same appearance as the side shown in Figure 1.

I claim:

The ornamental design for an animal pull toy, as shown and described.
